THERMOSTATICALLY OPERATED ELECTRICAL DEVICE

Emil Klahn, New Vernon, N. J.

Application July 26, 1926, Serial No. 124,917
Renewed November 15, 1934

4 Claims. (Cl. 200—122)

This invention relates to thermostatically operated switches and signalling apparatus operated thereby and has for its principal objects the provision of thermostatic switches which are certain in operation, compact, durable and simple of construction, as well as the utilization of a thermostatic switch to intermittently operate a signalling apparatus. Further objects of the invention are the construction of a thermostatic switch without employing therein a bi-metallic thermostatic metal element. Various other objects and advantages are hereinafter specified.

My invention is fully set forth in the following description and drawings forming a part thereof, in which latter.

Figure 1 is a central longitudinal section, certain parts thereof being shown in elevation, of a signal employing two flashing lamps of different colors;

Fig. 1A is a diagrammatic view of the electrical circuit of the construction shown in Fig. 1;

Fig. 2 is a transverse section on the line 2—2 of Fig. 1;

Fig. 3 is a top plan view of the lower portion of the device with the socket portions removed; and

Fig. 4 is a bottom plan view of the base.

Referring to Figs. 1 to 4 of the drawings, the reference numeral 1 designates an apertured base plate to which is secured an apertured panel 1' of insulation material that bridges the aperture a. Distant from the recess is a socket member of a two-piece plug 2 adapted to receive a blade member such as is commonly secured to the end of a lamp cord whereby current is fed from any suitable source of supply into the lead wires, b, b' of the device.

An outer metal shell 3 is supported on said panel 1' and the same envelopes a threaded inner metal socket member 4 which is mounted on posts 5, 5'. A thimble 6 of hard rubber or other insulation material is threaded onto the outside of said socket 4 and projects between the latter and the inside of the shell 3 and at the same time its upper end serves as an abutment to engage the end of the porcelain shell 7 of a two-way socket member, in which latter is secured a central porcelain plug member 8, carrying a threaded metal sleeve 9 that is adapted to co-operate with the threaded metal socket 4, and to receive current conducted to said socket 4 through the post 5' which serves as a binding post for the negative current lead 55 b'. Said two-way socket is specially constructed

to render it possible to obtain alternate flashes from ordinary electric bulbs mounted therein, i. e. the plug 8 is provided with a central aperture 10 in which is positioned a metallic sleeve 11, the latter being provided with a terminal flange 11' at one end and being threaded at its upper end and provided with a terminal nut 12 which is adapted to abut against a shoulder c in the upper end of said recess 10. A positive binding post or bolt 13, having a threaded upper end 13', projects centrally through the central bore of the porcelain plug 8 and is threaded into the threaded sleeve 14 of a positive U-shaped spring contact member 15. Still another threaded metallic socket 16 serves as the other 15 or negative contact for the filament of a lamp, for example, a red electric bulb x, when the latter is mounted in said socket, as shown. The socket 16 is secured by means of an integral strip 16' to a bolt 17 that is mounted in the 20 supplemental porcelain plug 18 and the extension 19 of said socket is in snug engagement with the upper end of the sleeve 9 which in turn is in electrical communication through the post 5' with the negative lead b'.

A second U-shaped spring contact member 20 is also supported by said post 13, but is insulated therefrom by a sleeve 21 which surrounds the greater portion of the post 13 and is also insulated from the contact 15 by the insulating gasket 22. The inner end 20' of said contact 20 is offset obliquely to cause it to contact with the conductor strip 23, the opposite end of which latter engages the nut 12 and is thereby in communication, through the metallic tube 11, with the terminal ring 24 of a positive contact member 24' carried by a positive binding post 25. A threaded metal socket 26 is also secured to the plug 18 by means of a bolt 21 and said socket serves as a negative terminal for 40 the filament of a lamp, for example, a blue electric bulb y.

A thermostatic switch member serves to either alternately illuminate the respective blue and red lamps or, if the double socket 9 is removed 45 and an ordinary electric bulb inserted in the socket 9, to periodically illuminate such bulb. This thermostatic switch comprises preferably an arc-shaped heat-responsive element 30 of well known bi-metallic thermostatic metal and comprising strips of dissimilar material as an outer strip m of steel having a low index of expansion and an inner strip of brass n having a relatively high index of expansion. A bracket 31 has its vertical arm brazed or riveted to said

element 30 at a point adjacent to the center of the arc and is in turn secured by a post 32 to the panel 1'. A snapping membrane element 33, of ribbon steel, is mounted on the free ends 5 of element 30 and spans the intervening space. Said spring is normally deformed, preferably by centrally crimping the same so that the natural position assumed by the spring when the element 30 is cold in the absence of a stop, would 10 substantially correspond to the dash line position of Fig. 2. Said membrane 33 is preferably provided with precious metal contact points 34, 34'.

As shown, the ends of said membrane element 15 33 are not rigidly connected to the respective ends of the arc-shaped member 30, but merely project into slots formed in the latter, whereby relative movement of the ends of said membrane element 33, with respect to the ends of the 20 arc-shaped element 30 in which they are mounted, is permitted, thus avoiding fatigue and crystallization of the membrane element adjacent its ends. However, as hereinafter described with reference to the construction shown in Fig. 8, 25 the membrane element may be integral with the heat-responsive element though the construction shown in Fig. 2 is for many purposes preferable.

Suitable heating means, for example, coils 35, 30 35' of bare nichrome wire are wound around the respective arms of the heat-responsive element 30, the same being separated from actual contact therewith by means of mica separators 36. The respective ends of said heating coil are 35 connected to binding posts 37, 38, the former binding post supporting a spring contact strip 39 that is adapted to normally engage the contact post 13, and the latter binding post 38 carrying a contact 38' which is adapted to periodically engage with the stop or contact 34. As 40 shown in Fig. 1A, the filament of the red lamp is in series with the coils 35, 35' and consequently, when the switch is in the position shown in this figure, the current will pass 45 through the coils and through the filament of the red lamp, thus illuminating the latter, but when the membrane member is in engagement with the stop 40, the current will pass through the filament of the blue lamp, thus illuminating 50 the same and no current will flow through the filament of the red lamp or the heating coils 35 and 35'. The initial position of the switch when cold is that shown in Fig. 1A and as the heat-responsive arms are heated by the coils 35 and 55 35', the said arms will expand and the snapping membrane element will suddenly snap into the position wherein the contact point 34' thereof will engage the contact 40, in which position the circuit, through the coils 35, 35' will be broken 60 thereupon the arms will commence to cool and consequently contract, and as this progresses, the critical point will be reached wherein the membrane 33 will suddenly snap from its engagement with the contact 40 and suddenly engage the contact 38'.

The position of the contact 38' should preferably be such that when the arms of the heat-responsive element 30 gradually heat up and move slowly outwardly, the contact point 34, carried by the membrane 33, will snap away 70 from the contact 38', thus making a sudden break between the contacts 34 and 38' and a sudden make between the contacts 34' and 40. As the arms cool down while the circuit is closed 75 through the contacts 38' and 40, the latter being

connected through the strip 41 with the binding post 25, the contact 34' will in turn suddenly snap out of engagement with the contact 40 and the contact 34 will snap into engagement with the contact 38'.

In the construction shown in Figs. 1 to 4 inclusive the membrane member 33, as shown, is deformed by crimping or distorting the same so that the natural position of such membrane, if unconfined, would substantially correspond to 10 the dash line position shown in Fig. 2 and consequently, when the membrane is forced in the position shown in full lines in Fig. 2 as a result of the pressure of the cold thermostatic arms of the thermostatic member 30, such membrane will 15 be in an unnatural or strained position and upon the least provocation, such as occurs when the pressure of such arms becomes relieved upon the heating of the same, the contact 34 will tend to snap away from the contact 38' and consequently 20 snap into engagement with the contact 40 simply by virtue of the fact that both the contact 38' and the contact 40 are at the edges of the snapping or critical zone and the slightest cooling of the thermostatic arms beyond the point where 25 they exert sufficient pressure to hold the contact 34' in engagement with the contact 40 will result in a sudden movement of the membrane and snapping re-engagement of the contact 34 with the contact 38'.

The membrane member shown in Figs. 1 to 3 is preferably deformed by means of the deforming clamps, such as disclosed in my co-pending application, filed February 25, 1926, Serial No. 90,521 or in any other desired manner, no claim 35 being made herein to such deforming clamps as such.

The curvilinear contact strip or member 24' is preferably arranged so that a portion thereof normally extends in close proximity, either just 40 above or just below, the bottom of the shell 4 and consequently if, in lieu of the two-way socket member 7, an ordinary light bulb is threaded into the socket 4, it can be inserted sufficiently far therein to effect the slight buckling of the strip 24' with the result that it will directly engage the said shell which latter is in circuit with the binding post 5'. Accordingly, in lieu of the alternate periodic extinguishment and illumination of such lamp in consonance with 50 the movements of the membrane 33, the filament thereof will alternately glow brightly when the contacts 34' and 40 are in engagement with each other and be dimmed, but not extinguished, when the contacts 34 and 38' are in engagement, 55 since in the latter case the resistances 35, 35' will be cut into the circuit of the filament. Obviously, such a construction affords a convenient arrangement for automatically producing a high-low effect and of course, if desired, a plurality of lamps in parallel can be arranged in the circuit with such resistances in lieu of a single lamp so as to exaggerate the flickering effect thus produced.

Having thus described by invention, what I 65 claim and desire to obtain by United States Letters Patent is:

1. The combination comprising an electric socket an electric signalling device mounted in said socket, a snapping thermostatic switch 70 including a bi-metallic thermostatic element, and a resistance element for periodically supplying heat to the thermostatic element of the switch, the switch being adapted when the signalling device is in one position to periodically

- effect the operation of said signalling device when the circuit through the signalling device circuit is closed, and means adapted, when said signalling device is adjusted to another position to prevent the complete extinguishment thereof at any time while said circuit is closed and to effect the partial dimming of the signal emitted by said signalling device periodically in response to the movements of the switch.
- 5 2. The combination comprising an electric socket, an electric signalling device mounted in said socket, a snapping thermostatic switch for controlling the circuit of said signalling device, said switch including a bi-metallic thermo-
10 static element, an electric resistance directly associated with said thermostatic element for periodically heating the thermostatic element of the switch and means for periodically connecting the resistance element into the circuit and
15 producing an alternate intensive emission and dimming of the signal without breaking the circuit through the signalling device.
- 20 3. An electric light fixture having a multi-way socket, a snapping thermostatic switch associated with said socket, said switch including a bi-
metallic thermostatic element and a resistance-heating element, the latter being adapted to be periodically connected with the filament circuit of a lamp inserted in said socket in response to the snapping movements of said switch, means responsive to the movement of said switch for alternately opening and closing the circuit through different lamps mounted in said multi-way socket whereby a multi-colored flashing effect can be obtained.
- 10 4. The combination comprising an electric fixture provided with a multi-way socket, a plurality of electric signalling devices mounted in said socket, a snapping thermostatic switch associated with said socket, the same including a bi-metallic thermostatic element, a circuit common to at least two of said signalling devices that are mounted in said socket, the flow of current through said circuit being controlled by said switch and a resistance-heating element also
15 interposed in said circuit and adapted to periodically heat the bi-metallic thermostatic element in said switch.

EMIL KLAHN.
